Edgar V. C. S.

UNITED STATES PATENT OFFICE.

CHARLES H. STONEBRIDGE, OF NEW YORK, N. Y.

PNEUMATIC MATTRESS.

1,317,235.

Specification of Letters Patent. Patented Sept. 30, 1919.

Application filed May 9, 1919. Serial No. 295,904.

To all whom it may concern:

Be it known that I, CHARLES H. STONEBRIDGE, a citizen of the United States, and residing at New York, in the county of 5 Bronx and State of New York, have invented certain new and useful Improvements in Pneumatic Mattresses, of which the following is a specification, such as will enable those skilled in the art to which it 10 appertains to make and use the same.

This invention relates to what are known as pneumatic or similar mattresses, and the object thereof is to provide an improved device of this class which may be used 15 wherever such mattresses are required or as a substitute for a mattress made in any way, as for instance, in hospitals, vehicles or vessels or for domestic use; a further object being to provide a mattress of the class 20 specified which comprises a plurality of parallel inflatable bags, all of which are in communication through a transverse end member and adapted to be inflated through a single air inflating nozzle or valve device. 25 The invention is fully disclosed in the following specification, of which the accompanying drawing forms a part, in which the separate parts of my improvement are designated by suitable reference characters in 30 each of the views, and in which:—

Figure 1 is a plan view of a mattress made according to my invention with part of the construction broken away;

Fig. 2 a section on the line 2—2 of Fig. 1 35 and on an enlarged scale;

Fig. 3 a partial end view of the mattress looking at the head end portion thereof and showing a mattress partially in section and with parts of the construction broken away;

40 and,

Fig. 4 a view similar to Fig. 1 but showing a modification.

In Figs. 1, 2 and 3 of the accompanying drawing I have shown at *a* one form of my 45 improved mattress which comprises a body portion *a*² and head portion *a*³ and, in the practice of my invention, I provide a body casing *b* of any suitable waterproof fabric, preferably rubberized canvas, and this body 50 casing *b* is also divided into a body portion and a head portion, and the body portion is formed into separate parallel longitudinal compartments *b*² in which are placed rubber tubes *c*, and the head portion thereof forms

a single transverse compartment *b*³ which 55 is in communication with all of the rubber tubes *c*, and said head portion forms the pillow of the mattress.

The outer face of the head portion of the casing *b* is open as shown at *b*⁴ and adapted 60 to be closed by a lacing or lace cord *b*⁵, and inwardly of said opening at the top of the head portion at *d* is secured a flap *d*² of any suitable material which closes the opening *b*⁴ when the mattress is in use, and which is 65 shown in position to close said opening in Fig. 2.

The head portion of the mattress is of the same length as the transverse width of the body portion thereof and placed in said head 70 portion is a tubular lining casing *e* of rubber or similar material, or of the same material as the tubes *c* are made of, and the tubes *c* are provided at their pillow ends with necks *c*², and the part *e* with corresponding necks *e*², and the necks *c*² and *e*² of each tube *c* are connected by a central sleeve *f* inserted thereinto or over which said necks 75 are slipped, and an outer strip or band *f*² which incloses said necks and may be secured 80 theraround in any desired manner so as to securely bind the parts *c*² and *e*² together.

The pillow or head member of the mattress is provided at one end with an ordinary inflating nozzle or valve device *g* through 85 which said pillow or head end may be inflated, and in this operation all the parallel tubular members of the mattress body will also be inflated as will be readily understood, and in this way the air pressure in the entire 90 mattress may be maintained at the same degree at all times.

If at any time one of the tubular members *c* of the body of the mattress should become broken or damaged in any way, the 95 head portion of the mattress may be opened at *b*⁴ and the broken or injured tube *c* detached from the head portion of the mattress where the necks *c*² and *e*² are connected, and the broken or injured tube *c* removed, 100 and a new one inserted in its place, and in this way any of the tubular members of the body portion of the mattress may be renewed or repaired when necessary.

The construction shown in Fig. 4 is the 105 same in all respects as that shown in Figs. 1 to 3 inclusive, except that in this figure a tube *h* is substituted for the transverse head

or pillow portion of the mattress, and through this tube the tubular members *c* of the body portion of the mattress may be inflated as will be understood, and it will 5 also be seen that in Fig. 4, the outer casing *b* of the mattress is omitted but, in practice, the tubular members *c* in the body portion of the mattress shown in Fig. 4 will be inclosed in the body casing *b* as is shown in 10 Figs. 1 to 3 inclusive, and the connection between the tube *h* and the parts *c* at *h*² in Fig. 4 is exactly the same as the corresponding connection in Figs. 1 and 2, the tube *h* being composed of rubber and being provided 15 with the neck members *e*².

With my improvement I provide a pneumatic mattress which is simple in construction, efficient in use and which will be strong and durable and will not easily get out of 20 order or need repair, and which, when not in use may be compactly folded together for shipment or other purposes; and while I have shown and described the construction which I prefer to employ in carrying my 25 invention into effect, it will be understood that the invention is not limited to the details of construction herein shown and described, and changes therein and modifications thereof may be made, within the scope 30 of the appended claims, without departing from the spirit of my invention or sacrificing its advantages.

Having fully described my invention, what I claim as new and desire to secure by Letters Patent, is:—

1. A mattress comprising a body portion and a transverse end portion, said body and end portions being composed of a flexible casing, the body part of which is divided 40 into a plurality of separate longitudinal tubular sections, inflatable tubes placed in said sections, an inflatable member placed in

said end portion, and means for detachably connecting each of said tubes with said member.

2. A mattress comprising a body portion and a transverse end portion, said body and end portions being composed of flexible material, the body portion being divided into a plurality of separate longitudinal tubular sections which open into said transverse end portion, inflatable tubes placed in said sections, an inflatable member placed in said end portion, said tubes being provided with reduced necks, and said inflatable member being provided with a plurality of reduced necks, and means for joining said necks.

3. A mattress comprising a body portion and a transverse end portion, said body and end portions being composed of flexible material, the body portion being divided into a plurality of separate longitudinal tubular sections which open into said transverse end portion, inflatable tubes placed in said sections, an inflatable member placed in said end portion, said tubes being provided with reduced necks, said inflatable member being provided with a plurality of reduced necks, means for joining said necks, an inflating valve in said member and by means of which said member and said tubes may be inflated, said transverse end portion being open to permit of the insertion of said tubes and member therethrough, and means for closing said opening.

In testimony that I claim the foregoing as my invention I have signed my name in presence of the subscribing witnesses this 8th day of May 1919.

CHARLES H. STONEBRIDGE.
